ROUNDING MACHINE

Frederic E. Bertrand, Lynn, Mass., assignor to
 United Shoe Machinery Corporation, Paterson,
 N. J., a corporation of New Jersey

Application March 16, 1937, Serial No. 131,209

25 Claims. (Cl. 12—17)

My invention relates to machines by which work-pieces, such as soles or insoles for shoes, are produced with the desired peripheral contours.

5 In Letters Patent of the United States No. 2,057,665, Bertrand, October 20, 1936, is disclosed an apparatus by which an outsole is cut from sheet-material by one knife, while, simultaneously, a second knife produces in the material 10 an incision corresponding in outline to the periphery of an insole. It is an object of this invention to increase the range of sizes to which a machine of this character is applicable, especially as to large work, the apparatus being efficient, free from interference and convenient to operate. To this end, improvements are made 15 in the actuating mechanism for the knives, two pivoted arms being employed, one for each knife, these turning about an axis common to both; a spring for urging toward the work the knife 20 upon one of the arms, as the secondary knife or that for outlining the insole, is carried by an enclosure for the spring of the other arm, the connection between the thus-carried spring and its arm being made by an extensible member; 25 oscillation of the secondary arm about its pivot and movement of the knife-mounting upon the arm is controlled by a lever or member shiftable in a plane substantially parallel to that of the pattern; a handle by which this lever member 30 may be actuated is movable, as under the influence of a spring, to a normal, inactive position; effective connections are provided by which the controlling movement is transmitted from the lever to the knife-mounting; the knife is supported and adjusted by novel means; and said knife is caused to follow accurately the pattern through the use of a special link-support for its 35 block and an auxiliary spring acting upon the block. While my invention is especially applicable to machines in which two knives are employed, it is to be understood that some of its features may be utilized in single-knife apparatus.

In the accompanying drawings, illustrating one 40 of the several possible embodiments of my invention,

Fig. 1 is a broken, top plan view of the machine;

Fig. 2, an enlarged, vertical, sectional detail 45 through the pivotal support for the knife-arms;

Fig. 3, an enlarged detail in elevation, showing the mounting and controlling means for the secondary knife;

Fig. 4, an enlarged vertical sectional detail of 50 the controlling means for the secondary knife;

Fig. 5, a similar view on the line V—V of Fig. 1;

Fig. 6, an enlarged detail in elevation and with parts broken away, particularly showing the secondary knife-block and its supporting holder;

Fig. 7 is a perspective view, with the elements of the holder and the block separated;

Fig. 8, an elevation of one of the block-supporting links;

Fig. 9, a top plan view of the holder, and

Fig. 10, a broken, enlarged detail in elevation 10 of the spring for the secondary arm, together with its supporting and connecting means.

In Fig. 1, there appears at 10 the rotary knife-actuating table of the well-known Planet sole rounding machine with its pivoted member 12, upon which is movable the slide 14 revolute 15 under the influence of the table. The primary arm 16 with its knife 18 (Fig. 6), which, in the present apparatus and that of the previously mentioned patent, produces an outsole, is guided in its travel resulting from the rotation of the table by a horizontal pattern 20. This pattern 20 and an opposed insole-pattern 22 are mounted in a normally stationary position upon the frame of the machine, being movable relatively to each other to clamp for the operation upon it a blank W of sheet-material. The knife-arm 16 turns about an upward projection from the slide 14, this being furnished by a sleeve 24 which surrounds a pin 26 (Fig. 2). The pin has a head 25 extending over a secondary arm 19, to which it is secured by screws 28. At its lower extremity, the pin receives a screw 30, which, by engagement with the under side of the slide, holds the arm-assembly against displacement. The two arms are thus pivoted one above the other about a 30 common axis, they acting independently of each other, presenting the knives advantageously at all portions of the peripheries of the patterns and being equally capable of a wide range of movement to provide for the cutting of all sizes of 35 soles and insoles.

Carried upon the slide 14 below the arms 16 and 19 is a casing, of which the cover 32 is shown in Fig. 1 and containing the usual spiral spring 34 acting through a pinion 36 and gear-segment 45

38 to urge the knife 18 upon the arm 16 into active relation to the pattern 20 and to the work. On the slide 14 beyond the end of the arm 19 is carried a casing 40 containing a spiral spring 42 attached at its outer end to the casing. This 50

may be arranged as is best shown in Fig. 10 of the drawings. Turning upon the slide, in what may be an extension from the cover 32, is a vertical post 44 about which the casing 40 is rotatable. The inner extremity of the spring 42 55

is secured to the post. In the upper portion of the casing is a groove in which is fastened one end of a cord or cable 46, the other extremity of which is joined to the arm 19. The force of 5 the spring is thus applied to urge the free end of the arm 19 toward the pattern 22, the cord furnishing a flexible, extensible connection. The normal tension of the spring 42 may be varied by rotating the post, as by a wrench applied to a 10 squared portion 48, through the desired angle, at which it is retained by a spring-actuated detent 50 pivoted upon the slide and engaging some one of a plurality of notches formed in the periphery of a disk 52 fast upon the post. Said post may 15 be more securely fixed in its adjusted position by a pin 54 carried by the slide. All these tension-applying members may be so fully removed from the associated elements that there will be no interference, whatever the extent of movement.

20 At the outer end of the arm 19 are spaced upper and lower branches 56, 56 (Fig. 3), through which is a bore to receive a stem 58 forming a portion of a slide which is one element whereby a secondary or incising knife 60 is moved vertically into and 25 out of engagement with the material W. To force the slide down and the knife 60 toward the work, a spring 62 is contained in a bore in the stem 58, abutting at its upper end against a bridge-piece 64 rising above the upper arm-branch 56. To lift 30 the slide and thereby free the knife from the work, a plate 66 fast upon the upper extremity of the stem has extending downwardly from it a pin or projection 68 resting upon one arm of a lever 70. The lever is fulcrumed upon a horizontal spindle 35 72 and has a second arm of generally U-shape (Fig. 1) from which rises an extension 74 (Figs. 3 and 4). A horizontal link 76 unites the extension to one arm of a lever 78 fulcrumed for horizontal oscillation substantially parallel to the 40 plane of the patterns 20 and 22 about a post 80 extending upwardly from the arm 16 through a slot 82 in the arm 19. A second arm of the lever 78 is furnished by a handle 84. Preferably, the handle is pivoted upon an upstanding portion of 45 the lever and is normally turned inwardly out of the way by a spring 86. When the operator desires to withdraw the knife 60 from the work, he turns the handle outwardly through 180° and swings it horizontally to the right, as viewed in 50 Fig. 1. This, through the previously indicated chain of connections, tilts the lever 70 away from a stop-screw 88 threaded through the arm 19, against which it is normally held by the spring 62, and lifts the slide by engagement with the pin 55 68. When the point of the knife has been thus raised above the plane of the material, the plate 66 of the slide contacts with the bridge 64. The force applied to the handle 84 is now effective to turn the arm 19 anticlockwise about its pivotal 60 axis against the force of the spring 42, so the secondary knife-carrying elements are separated from the work by successive vertical and horizontal movements. The movement of the handle carries the arm of the lever to which the link 76 65 is attached past the axis of the post 80, so it is held until the operator turns it oppositely, thus freeing the arm 19 to be swung in by the spring 42 and allowing the slide 58, 66 to be lowered with the knife 60 by the spring 62. Upon release of 70 the handle by the operator, the spring 86 returns it automatically to its normal inward position.

75 Shown as forming a part of the slide 58, 66 is a carrier-arm 90 for the knife 60, this arm being normally secured to the stem 58 by a tapered pin

92. The arm may be adjusted upon the stem in two directions at right-angles to each other. A screw 94 threaded horizontally through the arm 19 varies the angular position of the carrier-arm 90, and consequently the amount by which the 5 knife 60 may be caused to lead the knife 18 circumferentially of the patterns in its action upon the work. It also resists the thrust produced as the knife 60 makes its cut. A vertical screw 96 is threaded into the carrier-arm and has upon it 10 spaced portions 98, 98 lying at opposite sides of a lug 100 projecting from the slide-plate 66. Rotation of the screw raises or lowers the arm to provide for a preliminary positioning of the knife 60 with respect to the plane of the work. After 15 these horizontal and vertical adjustments are effected, the arm is fixed upon the stem by the pin 92.

Referring particularly to Figs. 3, 6 and 7, the carrier-arm 90 has pivoted on it to turn about a 20 vertical axis a stem 102 rising from a holder 104. Guided in the holder between a vertical fixed wall 106 and a separable wall 108 is a knife-block 110. In this block, the horizontal shank 112 of the knife 60 may be fastened in the usual manner. 25 The block is supported upon the holder by a pair of links 114, 116 to oscillate toward and from the pattern 22. These links have a width substantially that of the block, and the opposite extremities of each are rounded at 118 to enter laterally and be retained by recesses 120 formed in both the holder and block. Abutting against a projection 122 from the block and a screw 124 threaded through a plate 126 attached to the outer end of the holder is a spring 128 urging the block 30 and knife toward the pattern, this spring passing through an opening 129 in the link 116. The holder has a face 130 somewhat extended horizontally. This, riding upon the periphery of the pattern, guides the knife 60 through the greater 40 part of its travel and by its horizontal extent prevents the knife from tilting unduly about a vertical axis and thereby maintains it in a definite angular relation. This desirable contact-length will, however, as may be seen upon reference to 45 Fig. 9, bridge across some portions of a pattern, as at the inside of a hollow shank. Up to this time, the greater force of the spring 42 will overcome that of the spring 128, and the effect will be as though the knife were secured directly in the holder. When bridging occurs, the spring 128 forces the rounded end 132 of the block out from the holder, and causes it and the knife 60 to follow accurately the concave portion of the pattern. Adjustable vertically in ways 134 upon the holder 50 104 is an arm 136 fixed in place by a slot-and-screw connection 138 and raised and lowered upon the holder by a screw 140, the head of which enters a slot 142 in its side. The arm 136 has a contact-face 144 upon the under side of its inner 60 end, which, resting upon the upper surface of the work-piece W, limits the downward movement of the knife 60 and therefore the depth of the incision outlining the insole.

When a rounding operation is to be performed 65 by the machine, the primary arm 16 is found held in its normal inactive position, as by the usual latch-lever 146, resisting the force of the spring 34, both knives 18 and 60 being removed from the patterns 20 and 22. The secondary arm 19 70 is drawn back and retained by the lever 78, with the mounting-slide 58, 66 and the intermediate elements raised, so the knife 60 is above the plane which the upper face of the work is to occupy. The patterns 20 and 22 are separated, and be- 75

tween them the operator inserts a work-piece W and clamps it in place. The lead of the insole-knife 60 or the extent to which it is out of vertical registration with the outsole-knife 18 5 will have been adjusted by the screw 94, and the approach of the insole-knife to the material by the screw 96, each of these varying the position of the carrier-arm 90 upon the mounting-stem 58. The arm 16 is released to transfer the knife 10 18 to its operative position, and the operator draws the handle 84 forward and turns it clockwise (Fig. 1) to carry the crank 78 past the center. This first permits the spring 42 acting through the cord 46 to draw the arm 19 into its 15 active position, with the knife 60 against the periphery of the pattern 22, and then the spring 62 to lower the mounting until the knife enters the material ready to produce its cut. The machine being started in operation, the table 10 and 20 the other supporting elements cause the travel of the two knives about their patterns, so the points of operation are shifted to form from the piece W an outsole and to outline in said piece an insole. At the convex and flatter concave portions 25 of the periphery of the pattern 22, the surface 130 of the holder 104 acts as a guiding means for the knife 60, the knife-block 110 being held back with its supporting links 114 and 116 by the excess of strength of the spring 42 over the spring 128. But when more abrupt concavities of the pattern interfere with the normal 30 relation of the holder and knife to the pattern, the spring 128 urges the block in beyond the surface 130, so its knife is caused to follow the correct path. When the machine stops, the operator reverses his acts above outlined, drawing 35 forward the handle 84, thus turning the lever 78 to successively lift the knife 60 from the material and swing out the secondary arm 19, then 40 withdrawing the arm 16 and knife 18. The patterns are separated, and the completed work removed.

Having described my invention, what I claim as new and desire to secure by Letters Patent of 45 the United States is:

1. In combination, two patterns, a support, two arms pivoted upon the support about an axis common to both, a knife mounted upon each arm, the knives being guided by the respective patterns, means for causing movement of the points of operation of the knives about the patterns, and means for urging each arm and its knife toward the corresponding pattern. 50

2. In combination, two patterns, a revolute support, a pin carried by the support, two arms surrounding the pin and movable one above the other upon the support, a knife mounted upon each arm, the knives being guided by the respective patterns, and a spring individual to each 55 arm for moving its knife toward the corresponding pattern.

3. In combination, two patterns, a revolute support, a pin rotatable in the support, a sleeve surrounding the pin, an arm pivoted about the 60 sleeve, an arm secured to the pin, a knife mounted upon each arm, the knives being guided by the respective patterns, and means for urging each arm and its knife toward the corresponding pattern.

4. In combination, two patterns, a support provided with a projection, two arms pivoted upon the projection, a knife mounted upon each arm and co-operating with one of the patterns, means for causing movement of the points of operation 70 of the knives about the patterns, a spring car-

ried by the support and acting upon one arm to urge its knife toward one of the patterns, and a spring carried by the support and acting upon the other arm to urge its knife toward the other pattern. 75

5. In combination, a pattern, arms revoluble about the pattern and movable toward and from said pattern about a common axis, a knife mounted upon one of the arms, and a spring carried by the other arm and acting to urge the knife 10 into co-operation with the pattern.

6. In combination, two patterns, two arms revoluble about the patterns and movable toward and from respective patterns about an axis common to both, a knife mounted upon each 15 arm and guided by its pattern, and a spring individual to each arm and acting to urge the knife thereof into cooperation with the pattern, the springs being supported at the ends of the arms. 20

7. In combination, two patterns, a revolute support provided with a projection, two arms pivoted upon the projection, a knife mounted upon each arm, the knives being guided by the respective patterns, a spring carried by the support and acting to urge one arm and its knife toward the pattern, a casing carried by an enclosure for the spring of the last-mentioned arm, a spring contained in the casing, and a flexible member joining the spring to the other arm. 25 30

8. In combination, a pattern, a pivoted arm revoluble about the pattern, a knife-mounting movable upon the arm, a knife carried by the mounting, means acting upon the arm and mounting to urge the knife into active co-operation with the pattern, and a member movable to control the oscillation of the arm about its pivot and the movement of the knife-mounting upon the arm. 35

9. In combination, a pattern, a pivoted arm 40 revoluble about the pattern, a knife-mounting movable upon the arm, a knife carried by the mounting, means acting upon the arm and mounting to urge the knife into active co-operation with the pattern, and a lever movable in a plane 45 substantially parallel to the pattern to control successively the oscillation of the arm about its pivot and the movement of the knife-mounting upon the arm. 50

10. In combination, a pattern, a pivoted arm 55 revoluble about the pattern, a knife-mounting movable upon the arm, a knife carried by the mounting, means acting upon the arm and mounting to urge the knife into active co-operation with the pattern, a member movable to control 60 the oscillation of the arm about its pivot and the movement of the knife-mounting upon the arm, and a handle pivoted upon the member to move between active and inactive positions. 65

11. In combination, a pattern, a pivoted arm 60 revoluble about the pattern, a knife-mounting movable upon the arm, a knife carried by the mounting, means acting upon the arm and mounting to urge the knife into active co-operation with the pattern, a member movable to control 65 the oscillation of the arm about its pivot and the movement of the knife-mounting upon the arm, a handle pivoted upon the member to move between active and inactive positions, and a spring urging the handle normally to its inactive 70 position.

12. In combination, a horizontal pattern, means for clamping work against the pattern, a pivoted arm revoluble about and movable toward and from the pattern, a knife-mounting mov- 75

able upon the arm to present the knife to the work and to withdraw it therefrom, a lever fulcrumed upon the arm to move horizontally and acting upon the mounting to withdraw the knife, 5 and a member movable horizontally to actuate the lever.

13. In combination, two patterns, a primary and a secondary arm revoluble about and pivoted to oscillate toward and from the respective 10 patterns, a knife carried by the primary arm and co-operating with its pattern, a knife-mounting movable upon the secondary arm, and a lever fulcrumed upon the primary arm and movable to turn the secondary arm about its pivot 15 and to shift the knife-mounting thereon.

14. In combination, two patterns, a primary and a secondary arm revoluble about and pivoted to oscillate toward and from the respective patterns, a knife carried by the primary arm and 20 co-operating with its pattern, a knife-mounting movable upon the secondary arm, a post extending from the primary arm through an opening in the secondary arm, and a lever fulcrumed upon the post and movable to turn the secondary arm 25 about its pivot and to shift the knife-mounting thereon.

15. In combination, a pattern, an arm revoluble about and movable toward and from the pattern, a slide movable upon the arm, a carrier 30 member mounted to turn upon the slide, means arranged to fix the carrier member in different positions upon the slide, a knife-holder arranged for pivotal movement upon the carrier member, and a knife carried by the holder and co-operating 35 with the pattern.

16. In combination, a pattern, an arm revoluble about and movable toward and from the pattern, a slide movable upon the arm, a carrier member mounted to turn upon the slide, 40 means arranged to fix the carrier member in different positions upon the slide, means arranged to limit variably the angular movement of the carrier member upon the slide, a knife-holder arranged for pivotal movement upon the carrier member, and a knife carried by the holder and co-operating 45 with the pattern.

17. In combination, a pattern, an arm revoluble about and movable toward and from the pattern, a slide movable upon the arm, a carrier 50 member mounted to turn upon the slide, means arranged to fix the carrier member in different positions upon the slide, means arranged to limit variably the angular movement of the carrier member upon the slide, means arranged to raise 55 and lower the carrier member upon the slide, a knife-holder arranged for pivotal movement upon the carrier member, and a knife carried by the holder and co-operating with the pattern.

18. In combination, a pattern, an arm revoluble about and movable toward and from the pattern, said arm having spaced terminal-portions 60 in which are alined openings, a plate having a guide-stem slidable in the openings, there being an extension from the plate, means contacting

with the extension to raise the plate, and a knife movable with the plate and co-operating with the pattern.

19. In combination, a pattern, an arm revoluble about and movable toward and from the pattern, said arm having an opening, a plate having a hollow guide-stem slidable in the opening, there being an extension from the plate, a spring situated in the stem and acting to urge the plate downwardly, means contacting with the plate-extension to raise the plate, and a knife movable with the plate and co-operating with the pattern. 5

20. In combination, a pattern, an arm revoluble about and movable toward and from the pattern, said arm having an opening, a plate having a guide-stem slidable in the opening, a carrier member variable in position upon the stem, a knife-holder pivoted upon the carrier member, and a knife carried by the holder and co-operating 15 with the pattern. 15

21. In combination, a pattern, an arm revoluble about and movable toward and from the pattern, said arm having an opening, a plate having a guide-stem slidable in the opening, a carrier member variable in position upon the stem, 25 a knife-holder pivoted upon the carrier member, screws carried by the arm and plate and arranged to vary the position of the carrier member in different directions, and a knife carried by the holder and co-operating with the pattern. 30

22. In combination, a pattern, an arm arranged to move toward and from the pattern, the arm and pattern having a relative operating movement, links mounted to oscillate upon the arm, a knife-block pivoted upon the links, a knife 35 fixed in the block, and means for forcing the block and knife into co-operation with the pattern.

23. In combination, a pattern, an arm arranged to move toward and from the pattern, 40 the arm and pattern having a relative operating movement, links mounted to oscillate upon the arm, one of the links being provided with an opening, a knife-block pivoted upon the links, a spring extending through the link-opening and acting upon the block to urge it toward the pattern, and a knife fixed in the block. 45

24. In combination, a pattern, an arm arranged to move toward and from the pattern, the arm and pattern having a relative operating movement, a holder mounted upon the arm and 50 provided with a guideway, a knife-block movable in the guideway, and links pivoted upon the holder and supporting the knife-block.

25. In combination, a pattern, a revoluble arm arranged to move toward and from the pattern, a holder mounted upon the arm and provided with a guideway, a knife-block movable in the guideway, links pivoted upon the holder and supporting the knife-block, and a spring interposed 55 between the holder and knife-block to urge the block toward the pattern. 60

FREDERIC E. BERTRAND.
